UNITED STATES PATENT OFFICE.

OWEN ANDREW YOUNG, OF EASTON, PENNSYLVANIA.

GRASS-CATCHER FOR LAWN-MOWERS.

SPECIFICATION forming part of Letters Patent No. 617,006, dated January 3, 1899.

Application filed June 30, 1898. Serial No. 684,835. (No model.)

To all whom it may concern:

Be it known that I, OWEN ANDREW YOUNG, a citizen of the United States, residing at Easton, in the county of Northampton and State 5 of Pennsylvania, have invented a new and useful Grass-Catcher for Lawn-Mowers, of which the following is a specification.

My invention relates to attachments for lawn-mowers, and particularly to a grass-catcher adapted to be applied to a lawn-mower of any ordinary construction and having means for collecting grass as it leaves the mowing devices and for periodically discharging the collected grass to form heaps or wind- 15 rows.

Further objects and advantages of this invention will appear in the following description, and the novel features thereof will be particularly pointed out in the appended 20 claims.

In the drawings, Figure 1 is a perspective view of a lawn-mower attachment constructed in accordance with my invention applied in the operative position to a lawn-mower. Fig. 25 2 is a sectional view showing the positions of the parts at mid-stroke during the discharging operation of the scraper.

Similar numerals of reference indicate corresponding parts in both figures of the drawings.

1 designates a laterally-flanged receptacle or drag provided at its front end with attaching-links 2, pivotally mounted upon the receptacle-flanges 3 near their front ends and 35 adapted for attachment at suitable points to the lawn-mower frame. Spanning the receptacle at an intermediate point is an arched supporting-frame 4, provided at its center with a bracket 5, terminating in a bearing 6, 40 and mounted in the bearing is the upper fulcrum-bar 7 of a scraper, normally disposed in a pendent position, but of a length greater than the distance between the bearing and the floor of the receptacle. In addition to the 45 fulcrum-bar said scraper consists of side toggle or jointed arms, having upper and lower members 8 and 9, connected at their lower ends by a follower-bar 10 to traverse the floor of the receptacle. In the construction illus- 50 trated the upper members of the toggle or jointed arms are bifurcated to receive the tongues on the contiguous extremities of the

lower arms, suitable pivot-pins 11 being engaged with the interlocking extremities of the members to allow the deflection of the joints 55 in either direction from the plane of the frame.

The jointed construction of the scraper provides for the mounting thereof in a fixed bearing on the frame of the receptacle, while allowing the follower-bar to traverse the floor 60 of the receptacle approximately throughout its length, the deflection of the arms of the scraper increasing as the follower approaches the vertical plane of the bearing and decreasing in opposite directions from this point until 65 the members of the arms are in alinement, as indicated in Fig. 1; also, the frame members of the scraper may be provided with any suitable filling (not shown) or may be open, as indicated in the drawings, a function of the 70 scraper, in addition to that of removing accumulations of grass from the receptacle, being to close the rear end of the receptacle during the operation of the mower, and thus cause cut grass thrown rearwardly from the 75 mower to drop into the receptacle.

Connected to the lower member of the scraper-frame, at an intermediate point between the lower edge of scraper bar or blade and the joint between the arm members, is 80 the front end of an operating-handle 12, such connection being pivotal and being accomplished by means of a bracket 13, projecting upwardly from the scraper or follower bar and being bifurcated to receive the extremity 85 of said handle. The operating-handle is also provided at its rear or free end with a hook 14 for engagement with an eye 15 on the lawn-mower handle 16 when the parts are in the normal position (indicated in Fig. 1) or with 90 the scraper or follower blade at the rear end of the receptacle.

When the scraper is in its normal position, as above set forth, to prevent the escape of grass from the receptacle, said scraper being 95 rearwardly and downwardly inclined, grass thrown rearwardly from the mower is caused to fall into the receptacle, and when a sufficient amount has accumulated the operating-handle of the grass-catcher should be disengaged from the lawn-mower handle and elevated to cause the blade to swing forward over the grass in the receptacle until it reaches a position in advance thereof, after which it is

lowered in front of the accumulated grass and is then drawn rearwardly to discharge the contents of the receptacle.

This forms a simple, inexpensive, and convenient device which may be applied with facility to a lawn-mower to enable the operator to collect the grass as it is cut, and thus avoid subsequent raking, the grass being deposited at intervals in piles or windrows, as preferred.

- 10 The jointed or toggle construction of the side arms of the sectional scraper provides not only for the rearward movement of the scraper or follower bar in contact with the floor of the receptacle, but the above-described elevation of said follower to pass it forwardly over a quantity of grass accumulated in the receptacle preparatory to the discharge of such contents by the rearward movement of the scraper.
- 20 The left-hand wall of the receptacle or drag is preferably made somewhat higher than the opposite wall, as approximately double the height thereof, for the reason that grass as it is cut by the knives is thrown to the left instead of directly to the rear, and I have found it desirable to guard against throwing the grass out of the receptacle by upwardly extending said left-hand wall.

Various changes in the form, proportion, and the minor details of construction may be resorted to without departing from the spirit or sacrificing any of the advantages of this invention.

Having described my invention, what I claim is—

- 35 1. A grass-catcher for lawn-mowers, having a receptacle provided with means for attachment to a lawn-mower, and provided with an arched frame, and a scraper journaled at its upper end upon said frame, and having 40 jointed or toggle arms and a lower follower or scraper blade for traversing the floor of

the receptacle, and an operating-handle connected to the lower member of the scraper at an intermediate point.

45

2. An attachment for lawn-mowers, having a drag or receptacle open at its rear end, and a sectional scraper having jointed or toggle side arms connected at their upper ends by a journal-bar mounted in a suitable bearing, and connected at their lower ends by a scraper or follower bar to traverse the floor of the receptacle, an operating-handle pivotally connected to the lower member of the scraper at a point between its lower edge and the joints of said side arms, and means for securing the scraper in its normal position at the rear open end of the receptacle, substantially as specified.

50

3. The combination with a lawn-mower, of a laterally - flanged receptacle having an arched intermediate frame, links loosely connecting the front end of the receptacle with the lawn-mower frame, a scraper journaled at its upper end in a bearing upon said receptacle-frame and having jointed or toggle side arms and a transverse follower or scraper bar to traverse the bottom of the receptacle, an operating-handle pivotally connected with the lower member of the scraper at an intermediate point, and means, consisting of an engaging hook and eye, carried respectively by the lawn-mower and operating-handles, for securing the scraper in its normal position at the rear end of the receptacle to prevent the accidental escape of accumulations in the receptacle, substantially as specified.

55

In testimony that I claim the foregoing as my own I have hereto affixed my signature in the presence of two witnesses.

OWEN ANDREW YOUNG.
